UNITED STATES PATENT OFFICE.

CHARLES E. ZIMMERMANN, OF SYRACUSE, NEW YORK.

MARKING-GAGE.

SPECIFICATION forming part of Letters Patent No. 349,330, dated September 21, 1886.

Application filed May 20, 1886. Serial No. 202,721. (No model.)

To all whom it may concern:

Be it known that I, CHARLES E. ZIMMERMANN, of Syracuse, in the county of Onondaga, in the State of New York, have invented 5 new and useful Improvements in Carpenters' Gages, of which the following, taken in connection with the accompanying drawings, is a full, clear, and exact description.

This invention consists in a novel construction of a gage designed for use in carpentry, and to accurately, quickly, and conveniently mark or print out the locations and outlines of mortises to be cut.

In the accompanying drawings, Figure 1 is 15 a plan view of my invention as employed for marking on a window-frame the mortise for the reception of the sash-pulley case. Fig. 2 is a face view of the gage. Fig. 3 is a side view of the same; and Fig. 4 is a transverse 20 section on line $\alpha\alpha$, Fig. 1.

Similar letters of reference indicate corresponding parts.

A represents a straight bar adapted to be inserted in the groove B, which is usually formed 25 in the vertical sides of the window-frame for the reception of the dividing strip between the two sashes of the window. One end of the bar A has secured to it a plate, a, which projects at right angles from opposite sides of 30 said bar, and forms laterally-projecting abutments thereon, for the purpose hereinafter explained. To the opposite end of the bar A are adjustably connected two arms, C' C', which project from opposite sides thereof, and are 35 provided with slots b b at right angles to the bar A, through which slots pass the screws c c, which fasten the said arms on the upper side of the bar. The free ends of the arms C' C' have integral with them or rigidly attached 40 to them bars C C, which are thus carried longitudinally by the sides of the bar A, and the under side of said bars are provided with pricking or marking points e e, which stand in rows parallel with the bar A, and are prop- 45 erly spaced, so that when pressed into the surface of the window-frame each impression of said points shall indicate the center into which to insert the point of the auger by which the mortise is to be bored out, as represented by 50 dotted lines in Fig. 1 of the drawings.

In using my invention the bars C C are to be set out from the sides of the bar A, to bring the rows of points e e to coincide with the lon-

gitudinal central lines of the mortises to be formed in the window-frame, and said arms 55 are to be clamped in their aforesaid position on the bar by tightening the screws c c. Then the bar A is placed into the groove B in a position to bring the plate a to rest against the shoulder d, formed at opposite sides of the end 60 of the groove B by the mortise D, cut in the side piece of the window-frame for the attachment of the top cross-piece of said frame. The bars C C are thus carried at the requisite distances from the mortise D to correspond to 65 the distance required between the top rail or cross-piece of the window-frame and the sash-pulley. After the gage is placed in its aforesaid position a blow or pressure applied to the back of the bar A causes the markers or points 70 e e of the bars C C to make their impressions in the surface of the side rail of the window-frame. A series of such side rails may thus be marked uniformly, accurate, and expeditiously, and if then, in boring out the mortises, the point of the auger is inserted 75 successively in the aforesaid impressions all the mortises will be true and uniform.

I do not limit myself to the adjustable attachment of the arms C' C' to the bar A, inasmuch 80 as a number of such bars may be provided with permanently-attached arms carrying the marking-bars C C different distances from the bar A. Neither do I limit myself to the employment of two marking-bars at opposite 85 sides of the bar A, because in some cases only one of said marking-bars may be required.

What I claim as my invention is—

The within-described carpenter's gage, consisting of the bar A, provided at one end with 90 the laterally-projecting abutment a, the laterally-projecting arms C' C', adjustably connected to the opposite end of the bar A, and the marking bar or bars C C, arranged longitudinally by the side of the bar A and rigidly attached to the arms C' C', substantially as specified and shown.

In testimony whereof I have hereunto signed my name and affixed my seal, in the presence of two attesting witnesses, at Syracuse, in the 100 county of Onondaga, in the State of New York, this 18th day of May, 1886.

CHARLES E. ZIMMERMANN. [L. s.]
